(57) **CLAIM**

We claim the ornamental design of a ANSI STI bearing frame, as shown and described.

DESCRIPTION

FIG. 1 is a perspective view of a bearing frame showing the present invention;

FIG. 2 is a perspective view of the bearing frame in FIG. 1 rotated counterclockwise into the page about 90° showing the present invention;

FIG. 3 is a side view of the bearing frame in FIG. 1 showing one side of the present invention;

FIG. 4 is a side view of the bearing frame in FIG. 1 showing the other side of the present invention;

FIG. 5 is a front-to-back view of the bearing frame in FIG. 2 along its longitudinal axis looking into the page showing the present invention;

FIG. 6 is a front-to-back view of the bearing frame in FIG. 1 along its longitudinal axis looking into the page showing the present invention;

FIG. 7 is a bottom of the bearing frame in FIG. 1 showing the present invention; and,

FIG. 8 is a top view of the bearing frame in FIG. 1 showing the present invention.
